KEYING CHOKER

Application filed December 1, 1925, Serial No. 72,459, and in Germany December 5, 1924.

In installations utilizing extra high frequency currents, the suggestion has been made to use an iron-enveloped conductor as the keying or telephony modulator. Such a device, in the presence of frequencies as here 5 coming into consideration, possess a considerable inductive and ohmic resistance, which may be neutralized by saturating the iron by a sufficiently large superposed auxiliary field, preferably a direct current field.

10 In this scheme, however, the difficulty is encountered that, if the controlling current is fed into the same conductor as the high frequency current, the two currents must approximately be of the same order of magnitude, while, on the other hand, it is desirable 15 to work with by far smaller controlling currents.

Now, this difficulty is obviated according to 20 the invention by exciting the iron body surrounding the high frequency conductor with a separate control current coil producing an auxiliary field of two or more poles.

The accompanying drawing illustrates two 25 embodiments of this idea, Fig. 1 referring to the two-pole excitation of the auxiliary field, while Fig. 2 shows an arrangement for multi-pole excitation.

Referring to the figures, *a* stands for the 30 high frequency conductor, *b* the iron body enveloping the same, while *c* is the control-current coil. It is preferable to build the latter of a bare conductor arranged upon a carrier consisting of porcelain or a similar 35 refractory insulator.

Having thus described my invention, what I claim is:—

1. In a high frequency modulation system, a high frequency conductor of non-magnetic 40 material, a magnetic material having a portion thereof enveloping said conductor and another portion thereof extending outwardly from the portion enveloping said conductor and forming a closed magnetic path with 45 said first named portion, and means independent of said high frequency conductor associated with said extending portion of said magnetic material for controlling the magnetic saturation of said material and modulating the said high frequency flowing

through said high frequency conductor thereby.

2. In a high frequency modulation system a path of high frequency currents, an iron body enveloping said high frequency current path and having a portion extending outwardly therefrom and forming a closed circuit for magnetic currents, control current means associated with said extended portion of said iron body for saturating the same in varying degrees in accordance with said current strength, whereby the lines of magnetic flux extend transverse to said conductor at all times and the high frequency current flowing through said conductor is modulated in accordance with the varying degrees of saturation in said iron body and control currents of substantially lesser magnitude than said high frequency currents are provided.
